[57] **CLAIM**

The ornamental design for a set of computer speakers, as shown and described.

DESCRIPTION

FIG. 1 is a perspective view of a first speaker of a set of computer speakers, showing my new design;

FIG. 2 is a front elevational view thereof;

FIG. 3 is a left side elevational view thereof, the right side being a mirror image thereof;

FIG. 4 is a rear elevational view thereof;

FIG. 5 is a top plan view thereof;

FIG. 6 is a bottom plan view thereof; and,

FIG. 7 is a front, left side and top perspective view of the second speaker of a set of computer speakers, the undisclosed right side view being a mirror image of the left side, and the rear and bottom views being the same as the first speaker except for the control buttons.
